CLAIM

The ornamental design for a LED lamp tube, as shown and described.

DESCRIPTION

FIG. 1 is a top, front and right side perspective view of a LED lamp tube showing my new design;

FIG. 2 is a bottom, front and left side perspective view thereof;

FIG. 3 is a front elevational view thereof;

FIG. 4 is a left side view thereof;

FIG. 5 is an enlarged top plan view thereof;

FIG. 6 is an enlarged bottom plan view thereof; and,

FIG. 7 is an enlarged cross-sectional view taken along line 7-7 of FIG. 3.

The broken lines in the drawings illustrate portions of the LED lamp tube which form no part of the claimed design, and the break lines indicate that the LED lamp tube have no specific length. Further, The LED lamp tube is shown with a symbolic break in its length. The appearance of any portion of the article between the break lines forms no part of the claimed design.

The diagonal lines indicate transparency.
